MATHER GARLAND

BY Charles E. Gill
ATTORNEY

UNITED STATES PATENT OFFICE.

MATHER GARLAND, OF CHICAGO, ILLINOIS, ASSIGNOR TO GARLAND VENTILATOR COMPANY, OF CHICAGO, ILLINOIS, A CORPORATION OF ILLINOIS.

VENTILATING APPARATUS.

Application filed October 8, 1923. Serial No. 687,096.

The invention pertains particularly to a special ventilating of the closed bodies of automobiles. It is commonly known that the air in closed bodies of automobiles very quickly becomes vitiated and foul, and the object of my invention is to provide ventilating means in the roof or top of the body which, while the automobile is in motion, will constantly and efficiently exhaust the vitiated air from within the body and constantly maintain an adequate volume of fresh air within said body, the fresh air being induced to enter the body by reason of the said exhaust.

15 A further object of the invention is to provide ventilating means which while entirely effective, do not mar or require any change in the approved lines or appearance of closed automobile bodies, the apparatus 20 of my invention not necessitating the use of any parts projecting from either the top or sides of the closed body.

In carrying out my invention I conceal the ventilating means within the roof of 25 the vehicle, between the upper and lower layers of the material thereof, so as not to mar or detract from the usual appearance of the body, and within the ceiling of the closed body I apply a suitable grid which 30 is in communication with one portion of my apparatus and through which the vitiated air is exhausted and discharged. I utilize the speed or movement of the vehicle for exhausting the vitiated air from the closed 35 body and inducing a flow of fresh air into said body, and to this end, in the preferred form of my invention, I provide or construct within the roof of the body two air-conduits which are open at their forward or 40 intake ends at the front edge of said roof and thence extend rearwardly and laterally and are open at their other or discharge ends at the side edges of said roof, and a transversely extending air-conduit which is in 45 communication with the interior of the closed body through said grid and opens at its ends through the side edges of the roof adjacent to the said discharge ends of the two first mentioned conduits, so that the 50 strong air-currents leaving said discharge ends may compel an outward flow of air from the body through the ends of said transverse conduit. The air-conduits which

open at the front edge of the roof preferably have rather large intake openings and thence are reduced in cross-sectional area toward their discharge ends so as to effect a strong blast-like exit of the air at said ends, and the transverse air-conduit is preferably subdivided by a partition at the grid as a safeguard against the possible effects of a strong wind blowing directly against the side of the vehicle body.

The invention embodies, also, certain details of form and construction tending to increase its efficiency, and is also capable of modification as to its form and details, and the invention will be fully understood from the detailed description hereinafter presented, reference being had to the accompanying drawings, in which;

Fig. 1 is a perspective view of a portion of an automobile whose closed body embodies in its roof construction one desirable form of my invention;

Fig. 2 is a side elevation, partly in section and partly broken away, of the same, the section being on the dotted line 2-2 of Fig. 3;

Fig. 3 is a top plan view, partly in horizontal section and partly broken away, of the same;

Fig. 4 is a vertical transverse section through the same taken on the dotted line 4-4 of Fig. 3;

Fig. 5 is a horizontal section through a modified construction of ventilating apparatus embodying my invention, and modification becoming apparent by a comparison of Figs. 3 and 5;

Fig. 6 is a like view of a further modified form of my invention, and

Fig. 7 is a like view of another modified form of my invention.

In the drawings I illustrate my invention as embodied in the top or roof construction of a closed automobile body of "sedan" type, but it is to be understood that the invention is applicable for and extends to the top or roof construction of all closed automobile bodies whether of sedan, limousine, brougham or other type.

In the drawings 15 designates the closed body portion of an automobile, and 16 the roof or top thereof. My invention is embodied in the top 16 and its purpose is to

2
very efficiently ventilate the interior of the body 15 by a constant exhaust of the vitiated air therefrom while the automobile is in motion, the exhaust of the vitiated air operating to induce a flow of fresh air into the body, whereby an adequate volume of fresh air is maintained within said body.

The ventilating apparatus of my invention, in a preferred form thereof, is shown 10 in Figs. 1, 2, 3 and 4, wherein 17, 18 designate two intake air-conduits and 19 indicates a transversely extending eduction air-conduit which is in communication with the interior of the body 15 through a suitable grid 15 20 secured in the ceiling 21 of said body. The conduits 17, 18, 19 are preferably of limited depth or shallow so as to be concealed within the roof or top 16 without modifying the external appearance of the 20 same, and said conduits are of considerable cross-sectional area so as to permit air in adequate volume for the purposes of the invention to flow through them. The conduit 19 is preferably subdivided by a longitudinal 25 partition 22, centrally above the grid 20, into two sections or conduits 23, 24, whose outer ends 25, 26 are open at the side edges of the top or roof 16. In the absence of the 30 partition 22 the conduit 19 will be continuous and its ends will be the open ends 25, 26. I prefer to make use of the partition 22 to aid in equalizing the exhaust of the air from the body 15 and more particularly to guard against the possible effects, 35 when a continuous passage through the conduit 19 is present, of a very strong wind blowing directly against the side of the vehicle and possibly entering one end of the conduit. The partition 22 breaks the passage 40 through the conduit 19 and hence will prevent a strong wind from passing therethrough. The invention is not limited to the presence of the partition 22 since said partition will not usually be necessary and 45 may be dispensed with.

The conduits 17, 18 are preferably of cowl-shape, and at their wide forward or intake ends are open through the front edge of the roof or top 16, as shown in Figs. 1 and 50 3, and thence said conduits extend longitudinally in a rearward direction and then laterally in opposite directions, and at their discharge ends 27, 28 open through the side edges of the roof or top 16 directly at the 55 front of the discharge openings 25, 26 of the conduit 19 or of its subdivisions 23, 24 should the partition 22 be made use of. Between the oppositely curved back members 59, 30 of the respective conduits 17, 18 is formed a triangular space which I block off 60 by means of the transverse partition 31, so that said space may not impair the operation of the conduit 19, whose forward edge is defined by the said partition 31 and the laterally 65 extending back portions of the conduits

17, 18. The conduits 17, 18 preferable taper from their intake ends to their discharge ends so that the air may issue from said discharge ends with considerable force.

In the preferred construction of the conduits 17, 18, instead of making the back members or walls 29, 30 thereof continuous, I interpose therein one or more deflecting plate sections 32 (Fig. 3) whose inner ends are spaced from the main back walls of the conduits to form eduction channels or ports 33 and lie behind the adjacent surfaces of the back of the conduits, and whose outer ends are spaced from the adjacent walls of the conduit to form eduction channels or ports 34 and lie forwardly of the adjacent surfaces of the conduits. The deflectors 32 constitute portions of the back walls of the conduits 17, 18 and they are provided in order to produce the eduction ports 33, 34 which are in communication with the exhaust conduit 19 and through which portions of the exhaust air are induced to enter the conduits 17, 18 and be discharged therefrom with the air which enters the intake ends of said conduits 17, 18.

In the operation of the apparatus hereinbefore specifically described, air will enter the intake ends of the conduits 17, 18 while the automobile travels forwardly and will flow through and be discharged from said conduits with considerable force, this force serving to create an exhaust from the ends of the eduction conduit 19 quite sufficient to effect a constant suction of the air from within the vehicle body up through the grid or outlet 20 therefor and into the eduction conduit 19 from which said air in constant flow will be forcibly withdrawn by the action of the strong air currents leaving the conduits 17, 18. The speed of forward travel of the automobile determines the strength of the air currents leaving the conduits 17, 18 and the cubic feet of air exhausted from within the vehicle body per minute, and I have found in practical use that with the automobile traveling at moderate lawful speed, the action of the apparatus is such that the air within the closed body 15 is maintained pure and fresh.

The apparatus described is shallow and confined within the top of the closed body 15 and is such that it does not modify the shape or outlines of said top, this being an important advantage of the invention.

The conduits 17, 18, 19 are formed of sheet metal and they preferably follow or conform to the curved upper surface of the roof or top 16, as shown in Fig. 4, and hence any dust or rain entering the intake ends of the conduits 17, 18 will readily be discharged from the apparatus by the air flowing therethrough.

The form of the apparatus shown in Fig. 5 is substantially the same as that illustrated

in Fig. 3, with the exception that the back walls of the intake conduits in Fig. 5 are continuous instead of having the interposed deflecting sections 32 shown in Fig. 3, and hence the construction and operation of the modification shown in Fig. 5 will be understood without repeated description. The forward converging ends of the back walls of the intake conduits shown in Fig. 5 meet

10 at a point 35 which sets back from the front end of the apparatus, whereas in the construction shown in Fig. 3 the converging point 36 of the back walls of the intake conduits is at the front edge of the apparatus.

15 In Fig. 6 I illustrate a modified construction of my apparatus wherein I subdivide the exhaust or eduction conduit at the sides of the exhaust-opening 37 by partitions 38 extending lengthwise of the conduit, and 20 wherein, also, instead of employing the one deflector section 32 in the back wall of each intake conduit as shown in Fig. 3, I interpose two of said deflector sections, numbered 39, in the back wall of each intake 25 conduit, thereby to provide an increased number of eduction ports, numbered 40 in Fig. 6, leading from the eduction conduit into the intake conduits. The operation of the form of the apparatus shown in Fig. 6 30 will be readily understood from the foregoing description of the form of the apparatus shown in Figs. 1 to 4 inclusive, the differences between the two constructions residing in minor details.

35 In the modification shown in Fig. 7, the intake conduits 41 diverge rearwardly from each other on straight lines instead of on the curved lines shown in the foregoing figures of the drawings, and the exhaust or 40 eduction conduit 42 has straight front and rear walls 43, 44 instead of being partly defined by the back walls of the intake conduits, as in constructions hereinbefore described. The general operation of the apparatus shown in Fig. 7 is the same as that of the apparatus shown in Figs. 1, 2, 3 and 45 4, but I regard the form of apparatus shown in Figs. 1 to 6 inclusive as being more desirable than that shown in Fig. 7, especially 50 for limousines or automobiles having large bodies.

My invention may be embodied in other forms than those I have presented, and hence I do not limit my invention to the details 55 of form and construction shown and described and desire to secure adequate protection for my invention.

I preferably construct the ventilating apparatus as a unitary structure ready to be 60 built into the roof of a closed passenger-body 15, said apparatus comprising the top and bottom plates, as shown, between which the side walls of the several conduits are permanently located.

65 In the claims I refer to the intake con-

duits as induction conduits, because the strong air currents passing through these conduits induce the flow of vitiated air from the closed passenger-body 15 out through the eduction conduits.

70

What I claim as my invention and desire to secure by Letters Patent, is:

1. A closed automobile passenger-body having embodied in its roof structure and substantially concealed therein, a ventilating apparatus comprising an induction conduit which opens in the extreme front edge of said roof and discharges through the side edge thereof and an eduction conduit in communication with the interior of said body and having its discharge in the side edge of said roof and exposed to the force of the air flowing through said induction conduit, whereby an exhaust through said eduction conduit is maintained while the automobile 80 is in forward travel.

75

2. A closed automobile passenger-body having embodied in its roof structure and substantially concealed therein, a ventilating apparatus comprising an induction conduit which opens in the extreme front edge of said roof and discharges through the side edge thereof and an eduction conduit in communication with the interior of said body and having its discharge in the side 90 edge of said roof immediately in rear of the discharge end of said induction conduit, whereby the force of the air flowing through the induction conduit during the forward travel of the automobile sets up and maintains an exhaust through said eduction conduit.

95

3. A closed automobile passenger-body embodying in its roof structure a ventilating apparatus comprising an induction conduit which opens at the front and discharges at the side of the vehicle and an eduction conduit in communication with the interior of said body and discharging at the side of the vehicle immediately in rear of the discharge end of said induction conduit and also being in communication with said induction conduit, whereby the force of the air flowing through the induction conduit during the forward travel of the automobile 100 sets up and maintains an exhaust through said eduction conduit.

105

4. A closed automobile passenger-body having embodied in its roof structure and substantially concealed therein, a ventilating apparatus comprising two induction conduits which open in the extreme front edge of said roof and thence extend rearwardly and laterally to and discharge through opposite side edges of said roof, and eduction 120 conduit means in communication with the interior of said body and having discharges through opposite side edges of said roof and exposed to the force of the air flowing from said induction conduits, whereby an 125

130

exhaust through said eduction conduit means is maintained while the automobile is in forward travel.

5. A closed automobile passenger-body having embodied in its roof structure and substantially concealed therein, a ventilating apparatus comprising two induction conduits which open in the extreme front edge of said roof and thence extend rearwardly and laterally to and discharge through opposite side edges of said roof an eduction conduit means in communication with the interior of said body through the ceiling thereof and discharging through opposite side edges 10 of the roof immediately in rear of the discharge ends of said induction conduits, whereby the force of the air flowing through the induction conduits during the forward travel of the automobile sets up and maintains an exhaust through said eduction conduit means.

6. A closed automobile passenger-body having embodied in its roof structure and substantially concealed therein, a ventilating apparatus comprising two induction conduits which open in the extreme front edge of the roof and thence extend rearwardly and laterally to and discharge through opposite side edges of the roof and a transverse eduction conduit extending across the vehicle in rear of said induction conduits and discharging through the side edges of the roof immediately in rear of the discharge ends of said induction conduits, said eduction conduit at about its middle portion being in communication with the interior of said body through the ceiling thereof, for exhausting the air from said body.

7. A closed automobile passenger-body having embodied in its roof structure a ventilating apparatus comprising two induction conduits which open in the extreme front edge of said roof and thence extend rearwardly and laterally to and discharge through opposite side edges of the roof and eduction conduit means in communication with the interior of said body through the ceiling thereof and discharge through opposite side edges of the roof immediately in rear of the discharge ends of said induction conduits, whereby the force of the air flowing through the induction conduits during the forward travel of the automobile sets

up and maintains an exhaust through said eduction conduit means, said ventilating apparatus being a unitary structure to be introduced within said roof between the upper and lower layers thereof and composed of upper and lower plates between which the walls of the conduits are formed and the whole being adapted to be concealed within the roof of the body.

8. A closed automobile passenger-body embodying in its roof structure a ventilating apparatus comprising two induction conduits which open at the front of the vehicle and thence extend rearwardly and laterally to and discharge at opposite sides of the vehicle and a transverse eduction conduit extending across the vehicle in rear of said induction conduits and discharging at the sides of the vehicle immediately in rear of the discharge ends of said induction conduits, said eduction conduit at about its middle portion being in communication with the interior of said body through the ceiling thereof, for exhausting the air from said body, said ceiling having an opening protected by a grid for establishing communication with said eduction conduit and said conduit being subdivided above said grid by a partition.

9. A closed automobile passenger-body embodying in its roof structure a ventilating apparatus comprising two induction conduits which open at the front of the vehicle and thence extend rearwardly and laterally to and discharge at opposite sides of the vehicle and a transverse eduction conduit extending across the vehicle in rear of said induction conduits and discharging at the sides of the vehicle immediately in rear of the discharge ends of said induction conduits, said eduction conduit at about its middle portion being in communication with the interior of said body through the ceiling thereof, for exhausting the air from said body, and said eduction conduit also being in communication with the induction conduits through eduction ports formed in the back walls of said induction conduits.

Signed at Boston in the county of Suffolk and State of Massachusetts, this 5th day of October, A. D. 1923.

MATHER GARLAND.
